UNITED STATES PATENT OFFICE.

ALGERNON S. PHELPS, OF CHICAGO, ILLINOIS.

ACETYLENE-GENERATOR.

1,122,152.

Specification of Letters Patent. Patented Dec. 22, 1914.

Application filed September 17, 1909. Serial No. 518,168.

To all whom it may concern:

Be it known that I, ALGERNON S. PHELPS, a citizen of the United States, residing at Chicago, in the county of Cook and State of Illinois, have invented certain new and useful Improvements in Acetylene-Generators, of which the following is a specification.

My invention relates to improvements in gas generators and, in particular, to acetylene generators.

The object of my invention is to provide an acetylene generator which will be capable of automatically controlling the generation of gas under all conditions of use, of maintaining a uniform gas pressure, of preventing a flooding of the generator, and, in short, a generator wherein safety is assured and which will automatically adjust itself to varying circumstances and demands.

With these objects in view, my invention resides in the features, details of construction, and combination and arrangement of parts which will first be described in connection with the accompanying drawings illustrative of one embodiment of the same, and then particularly pointed out in the claims.

In these drawings: Figure 1 is a perspective view of the generator complete with certain portions broken away to reveal the interior construction; Fig. 2 is a detached front elevation of the lower portion of the carbid magazine showing the carbid feeding device in detail; Fig. 3 is a rear elevation of the same parts; Fig. 4 is a side elevation of the same; Fig. 5 is a vertical section through Fig. 4; Fig. 6 is a side elevation with the parts in the position assumed when feeding; and Fig. 7 is a similar view when in the non-feeding position.

Referring to the drawings in detail, the main generator casing *a* is divided by the partition *a'* into two compartments, a lower generating chamber *a²* having an upward extending cylindrical portion *a³*, and an upper chamber *a⁴* serving as a receptacle and water seal for the gasometer to be hereinafter more specifically referred to.

Water is supplied to the generating chamber by means of a filling lip *b* and a pipe *b'* provided with a T, and extending at *b²* into the generator and terminating therein in an upturned nipple to form a trap. A removable plug *b³* closes one arm of the T, whereby to provide cleaning access to the inward extension *b²*.

The generating chamber is emptied through a pipe *c* closed by a gate valve *c'*. This gate is normally locked by a foot *c²* formed on the rod *c³*. The rod *c³* is rigidly connected with the cock *d* controlling the vent pipe *d'* which leads from within the chamber *a²* above the water level by way of a T provided with a removable cleaning plug *d²*, and the cock *d* to the upper space 60 of the by-pass. The by-pass *e* is of the usual construction, being a tight box, arranged to be partially filled with water by a filter pipe *e'* terminating near the bottom of the box, and also having an outlet *e²*.

An outflow pipe *f*, tapping the inside of the generating tank at the maximum water level, leads by way of a T *f'*, having a removable cleaning plug *f²*, to the lower outside of the casing, where is situated another 70 T *f³*, thence the pipe extends upwardly to form a water trap and discharges at *f⁴* into the waste. By this construction the overflow water is taken from the top and the water trapped therein is comparatively free 80 from sediment which would not be the case if it were taken from the bottom of the generating chamber. This overflow pipe *f* is controlled by a cock *f⁵* interlocked by means of a rod *f⁶* with the rod *c³*. The two cocks 85 *f⁵* and *d* work in unison, being opened or closed by swinging rod *c³* about a vertical axis through its point of attachment to valve *d*. With the parts in the position here shown, it is obvious that the gate *c'* can not be 90 opened without first operating the said cocks to open the vent and also the overflow.

The gas, generated by the discharge of carbid into the water in the generating 95 chamber by the carbid feeding mechanism to be hereafter described in detail, passes by way of the pipe *g* through the washer *g'* and the filter *g²*, into the pipe *g³* to the T *g⁴* having vertically extending arms, one of which, 100 *g⁵* as a drip pipe extends into the water in the by-pass box *e* and the other, *g⁶*, is connected to the house supply pipe.

A blow-off pipe *h* having its inner open end terminating in the upper gasometer 105 space and surrounded by the usual hood *h'*, extends outside the gasometer to the T *h²*, having one vertical arm *h³* leading to the upper space of the by-pass and the other *h⁴* discharging out of doors into the atmosphere. 110

The gasometer *i* is of the usual general

2
form open at the bottom and floating, when filled with gas, within the receptacle a^4 , on a body of water which serves to seal the lower end. It is of annular shape, enveloping the washer g' and the filter g^2 and surrounding the cylindrical upward extension a^3 , of the generating chamber. A bail i' attached to the gasometer is detachably connected by the catch i^2 to an arm i^3 pivoted at i^4 to a bracket i^5 carried by the casing a and supported by the brace i^6 . The pivot i^4 is in the form of a removable pin attached to a chain i^7 to prevent loss.

Within the cylindrical extension a^3 of the generating chamber a^2 , the carbid magazine j is supported, and the atmosphere excluded by the cover j' . This magazine is of the usual cylindrical form in its upper portion with a converging or funnel-shaped lower portion ending in a chute j^2 . Within the lower portion of the magazine above the chute is suspended a shield j^3 to relieve the carbid in the chute j^2 from the pressure of the store or carbid in the upper part of the magazine.

25 The carbid feeding mechanism employed by me consists of the feed shoe k counterweighted at k' and supported by the yoke k^2 pivoted on the rod k^3 to swing below and a short distance from the mouth k^4 of the chute j^2 . Arms extending upwardly and forwardly from the shoe on each side of the discharge lip k^5 support a thin plate k^6 curved concentrically of the pivoted point of the shoe, the rod k^3 . This plate is mounted at a sufficient distance above the shoe k to enable it to reciprocate across the mouth k^4 closely contiguous thereto; and, being in front of the discharge lip k^5 of the shoe, the plate occupies a position beneath the mouth k^4 when the shoe k is withdrawn, as shown in Fig. 7, and is withdrawn to one side, as in Fig. 6, when the shoe is beneath the mouth. As shown, the discharge edge of the plate only slightly overlaps a straight line drawn through the discharge edge of the feed shoe radially to the point of support, the major portion of the plate extending in the opposite direction beyond and away from the feed shoe. Thus the plate k^6 forms a cut off for the carbid and, being rigidly fixed relative to the feed shoe, its operation is positive and absolute. A stop k^7 limits the extreme swing of the shoe by striking the magazine.

55 A T-shaped lever m is pivotally connected with the shoe at m' and on its head is provided with an escalloped or recessed face which is engaged by an arm m^2 of the rock shaft m^3 which is arranged to be rocked, upon the descent of the gasometer, in any approved manner, as for instance by a rod m^4 extending upwardly and connected to the yoke m^5 of the depending link m^6 pivoted to an arm m^8 pivoted in turn to the bracket i^5 . This arm m^8 may be bent or offset as at m^9 .

in such manner as to partially underlie the arm i^3 , and as the gasometer i and with it the arm i^3 descends, the rod m^4 is depressed and the shaft m^3 is rocked. A counter-weighted arm m^9 restores the shaft to its 70 normal position as soon as the gasometer again rises and releases the arm m^8 .

To prevent escape of gas and avoid the necessity of bushing, I employ a particular method of connecting the rod m^4 with the 75 rock shaft m^3 , making no claim to the same herein. Secured tightly to the rod m^4 is a downwardly opening hood m^{10} extending downwardly around the rod and telescopically into the well m^{11} to a point 80 below the water level in the gasometer. An upwardly extending pipe m^{12} fixed to the diaphragm or partition a' communicates between the gas space of the generating chamber a^2 and the upper 85 part of the hood m^{10} and the bore of the pipe serves as a passage for the rod m^4 . Below the partition a' the rock shaft m^3 is journaled in the bracket m^{13} and thus the rod m^4 has no sliding bearing in any part 90 requiring a bushing and the connection is effectually water sealed.

The relation of the parts just described is such that when the feed shoe occupies a non-feeding position beneath the mouth of the magazine, the cut off plate is retracted and the carbid may flow freely through the chute into the shoe. This is the normal situation when the gasometer is full of gas. As the gas is used and the gasometer descends, the shaft is rocked, the feed shoe is 95 swung to the rear by the T-lever from beneath the mouth of the magazine, dropping into the generating chamber the quantity of carbid which is in the shoe. This feeding movement of the shoe draws the cut-off plate simultaneously across the mouth of the magazine effectually shutting off any flow of carbid while the shoe is in its feeding position.

Ordinarily the shoe does not swing 110 through its full arc of movement, as the feed device is so sensitive that a very small deposit of carbid in the generating chamber is sufficient to close the shoe before it is emptied and to slightly open the cut-off, 115 while a very small consumption of the gas will cause the cut-off to close the chute and the shoe to feed another minute portion of its carbid. The result is the maintenance of an almost continuous feed and a consequent 120 highly desirable uniformity in the gas pressure in the service pipes so that flickering of the lights is avoided.

The water shed n cast integrally with the lower portion of the magazine extends as an 125 annulus around the magazine above the shoe and cut-off plate. This ring has formed in its upper side a groove n' and is arranged at a slight incline, discharging at n^2 in a spout beyond the shoe and cut-off. This 130

water shed serves to prevent access of water of condensation to the carbid or the shoe, and prevents accidental hydration of any carbid being fed from the magazine. This 5 water shed forms the subject matter of my divisional application Serial Number 865, 871, filed Oct. 9, 1914, and copending here-with.

Having thus fully described my invention, 10 what I claim as new and desire to secure by Letters Patent is:

1. In an acetylene generator, the combination, with the generating chamber, the carbid magazine, and the gasometer, of a shoe 15 having a closed bottom and an edge over which the carbid may discharge, said shoe being pivoted to swing beneath the mouth of the magazine, a cut-off device secured to the shoe, arranged to occupy a position beneath and close to the mouth of the magazine 20 when the shoe is withdrawn and to be withdrawn when the shoe is beneath the mouth, said cut-off device extending beyond and away from the feed shoe and having a 25 discharge edge only slightly overlapping the radial line through the discharge edge of the shoe, and means actuated by the movements of the gasometer to reciprocate the shoe and cut-off.
2. In an acetylene generator, the combination, with the generating chamber, the carbid magazine, and the gasometer, of a feed shoe pivoted to swing beneath the mouth of the magazine, a lever having an escalloped 30 T-head and pivoted by its stem to the shoe, an arm bearing against the escalloped head of the lever, and a connection between the arm and the gasometer to operate the lever whereby the shoe is reciprocated as the gasometer sinks.
3. In an acetylene generator, the combination, with the generating chamber, the car-

bid magazine, and the gasometer, of a feed shoe pivoted above the mouth of the magazine and arranged to swing to and fro beneath the mouth of the magazine at a distance therefrom, a sheet metal plate fixed to the shoe at one side thereof and above the same to occupy a position beneath and close to the mouth when the shoe is withdrawn 45 and to clear the same when the shoe is beneath the mouth, the cut-off plate being curved concentric to the pivotal mounting of the shoe, and means actuated by the movements of the gasometer to reciprocate the 50 shoe and cut-off, said means comprising a lever having an escalloped T-head and pivoted by its stem to the shoe to occupy a substantially horizontal position, a rock shaft having an arm bearing against the escalloped head of the lever, and a connection between the rock shaft and the gasometer.

4. In an acetylene generator, the combination, with a carbid magazine having a downwardly directed mouth, of carbid feeding 65 mechanism comprising a feed shoe mounted for reciprocation or oscillation at a distance below said mouth and having a discharge edge, a cut-off device rigidly secured to said feed shoe and arranged to move therewith 70 but closer to said mouth, said cut-off device having a discharge edge only slightly overlapping the discharge edge of the feed shoe and the major portion of the cut-off device 75 extending beyond and away from the feed shoe, and means for reciprocating said carbid feeding mechanism.

In testimony whereof, I affix my signature in the presence of witnesses.

ALGERNON S. PHELPS.
